UNITED STATES PATENT OFFICE.

CHRISTOPHER B. EDWARDS, OF COVINGTON, KENTUCKY, ASSIGNOR TO THE MOESCHL-EDWARDS CORRUGATING COMPANY, OF COVINGTON, KENTUCKY, A CORPORATION OF KENTUCKY.

SHEET-METAL ROOFING.

1,140,667.

Specification of Letters Patent.

Patented May 25, 1915.

Application filed March 13, 1915. Serial No. 14,263.

To all whom it may concern:

Be it known that I, CHRISTOPHER B. EDWARDS, a citizen of the United States of America, and a resident of Covington, in the county of Kenton and State of Kentucky, have invented a certain new and useful Improvement in Sheet-Metal Roofing, of which the following is a specification.

This invention relates to sheet metal roofing and more especially to the transverse joints made in the roof where the lower edges of the respective upper-sheets overlap the upper edges of the respective lower-sheets, and the object of the invention herein 10 is to provide an end-slip pocket or receptacle at the lower edge of each sheet to receive the upper edge of the next succeeding sheet below with the fastening nails driven through said lower edge of each upper-sheet just below the entrance of said pocket or receptacle so that the said nails are concealed beneath and covered by the upper edge of the next lower-sheet that is slipped into said pocket a suitable depth to assure 15 a close fitting and non-leaking joint, the further details of which will be fully herein-after described in connection with the accompanying drawings, in which—

Figure 1 is a fore-edge perspective view 20 of a roofing-sheet containing my invention, the upper end thereof being shown broken away in fragmentary-form from a somewhat larger fragment of the lower end, the latter end containing the essential pocket or receptacle feature of my device and including a lower-extension that is adapted to receive the fastening-nails; Fig. 2, a fragment of the lower portion of the sheet of metal used in making my form of roofing, such 25 sheet being notched or cut into at its opposite sides in the manner required to form folds or bends along the two dotted-lines A and B; Fig. 3, a longitudinal-section showing the lower portion of the sheet containing my improved pocket or receptacle for the upper edge of the next succeeding lower-sheet, the latter not being shown in this view and the upper end of the pocket-sheet being broken off; and Fig. 4, a view similar 30 to Fig. 3 but showing the upper edge of the lower-sheet duly pocketed or slipped into the receptacle provided in the lower edge of the upper-sheet and forming a joint laid on a section of sheathing into which latter

a nail is shown driven through the lower-extension of said upper-sheet.

1 indicates the body-portion of a roofing sheet having longitudinal crimps 2 and 3 along its opposite side-edges as shown only in Fig. 1.

4 indicates the upper end of the sheet and 5 the lower end thereof, both such ends being of the same structure with the exception that the lower end, (see the blank-form seen in Fig. 2,) is cut away at 6, 6 in its side-edges a short distance upward from its extreme lower edge and diagonal cuts 7, 7, converging toward each other upwardly are made in said blank beginning at the inner 10 upper corners of the cut-away notches or recesses 6, 6 and then the metal is bent forwardly along the transverse dotted-line B till it parallels with but does not touch the upper face of the lower portion 5 of the sheet, and then the metal is bent upwardly 15 along the transverse dotted-line A till it contacts with the already folded portion of the sheet, whereby a pocket or receptacle 8 is provided that forms an end-slit for receiving the upper end 4 of the next sheet below 20 and forming a lock-joint therewith. The crimps 2 and 3 at the sides are afterward made in the sheet and such crimps have space or pockets thereunder to receive the upper crimped ends of the next lower-sheet 25 the same as the middle pocket H in the main portion of the sheet.

In Fig. 4 I have designated the lower-sheet as 9 and numbered the fastening-nail as 10, the latter being driven into the lower-extension 5 at the points marked with the three crosses x, x, x shown in Fig. 1 but the upper end of the next lower-sheet is inserted or slipped into the pocket or receiving-slit 30 of the upper sheet.

The device is simple, easily and cheaply made and very readily applied. The fastening-nails are concealed beneath the upper end of each lower-sheet in the joint where the lap is made just ahead of the pocket-portion of the sheet and provision is thus made to reduce leakage to the minimum. The upper-sheet prevents the nails from accidental withdrawal from fastening place and a smooth as well as neat finish results.

I claim:

A metal-roofing sheet having longitudinal crimps along its opposite edges, and a back-

wardly and forwardly extending underfold made near the lower end thereof and with the plane body portion transversely notched and diagonally cut out at its side-edges from the said corrugated side-edges whereby a shallow transverse pocket is provided at the lower end of the sheet that is adapted to receive the upper end of the next succeeding lower-sheet in making a ready end-slip

transverse joint between sheets and with the fastening-nails duly covered and concealed by the said upper end of the said lower-sheet.

CHRISTOPHER B. EDWARDS.
